UNITED STATES PATENT OFFICE.

HUGH M. LAWTON, OF BELLEVUE, KENTUCKY, ASSIGNOR TO THE CINCINNATI TIME RECORDER COMPANY, OF CINCINNATI, OHIO, A CORPORATION OF OHIO.

TIME RECORDER.

Application filed November 14, 1921. Serial No. 514,887.

To all whom it may concern:

Be it known that I, HUGH M. LAWTON, a citizen of the United States, and a resident of Bellevue, in the county of Campbell and State of Kentucky, have invented certain new and useful Improvements in Time Recorders, of which the following is a full, clear, and exact description, reference being had to the accompanying drawings, forming part of this specification.

My invention relates to time recorders and more particularly to time recorders which are fully automatic requiring nothing more of the operator than to insert his card and pull down a platen hammer, with the machine taking care of the remainder of the operations.

My invention is based on clock actuation of the time wheels, clock actuation of an abutment member for the operator's card, clock actuation of an abutment member for a card tray locating piece, and platen operation of the tray locating piece. In connection with the card abutment I wish to refer for a more specific description thereof to my Patent No. 1,253,185 issued January 8, 1918, in which the advantages and structure of a continuously moving cam operator for a card abutment are fully dealt with.

As noted in the said patent, I move the abutment in a continuous manner and not by steps, and control the movement so that it is rapid at times of the day when the workers are going in and coming out, and slow or at rest when there is nothing to register except in the most isolated instances.

In the movable tray card abutment type of machine, explained in my said patent, a card is used that is ruled with lines for days of the week, and the time records are made in these columns that are so ruled. The cam moves the card tray so that the position of indications of In and Out, and irregular registrations, where rules of the shop would show the operator to have arrived at a later hour or left at an early one, become quickly distinguishable to the time keepers, and this system of registration has naturally a much greater flexibility than one wherein each registration must be

made within a given block or square of the card, and the card shifted for In, Out and Irregular, instead of being shifted for days of the week as per my system.

It is the immediate object of my invention to apply an automatic card tray shift for machines of the type of my former patent, thereby, as stated, making them fully automatic, but I do not wish my invention to be limited to the application of the card tray shift to one type of machine only.

In connection with the card tray shift, it is my object to provide for the least possible heavy duty of the clock, and in this connection I locate the tray by means of a prime mover connected with the platen hammer, and shift by means of the clock, a device which has no duty whatever except to act as an abutment for this prime mover.

In the past there have been several methods used of shifting a card tray, one of them being to shift a card tray locating member, which member was then forced by the platen hammer to do the duty of shifting the tray. Such a member had to have a rigidity of construction, which could not fail but be a strain on the operating parts.

Not only this, but the extent to which the platen hammer is relieved from duty renders the clock more useful, since a considerable strain on the platen handle renders all time recorders quite hard to operate under the most favorable conditions.

I accomplish my objects above stated by that certain construction and arrangement of parts to be hereinafter more specifically pointed out and claimed.

In the drawings,

Figure 1 is a front elevation of the machine.

Figure 2 is a side elevation taken from the platen operating handle side thereof.

Figure 3 is a detail front elevation showing the preferred form of locating device for the card tray.

Figure 4 is a face view of the locating abutment disk.

Figure 5 is a development on a straight line of the abutment post arrangement in a normal "day of the week" machine.

Figure 6 is a detail side elevation of the

operating device for the abutment member.

Figure 7 is a detail side elevation of the card abutment and clock connections therewith and with the card tray abutment 5 operating finger.

Figure 8 is a front elevation showing a detail of another form of card tray locating abutment.

Figure 9 is a side elevation illustrating 10 the means for operating the abutment devices of Figure 8.

Figure 10 is a detail front elevation showing one form of slide block or tray locating device carrier.

15 Figure 11 is a detail side elevation showing the parts illustrated in Figure 10.

Figure 12 is a face view of the form of abutment member shown in Figure 1 of the drawings.

20 Figure 13 is a plan view of one of the cards used in the machine with various time data thereon.

It will be noted that I have not attempted 25 to show in the drawings the various details of a time recorder, and that in each instance I have omitted the showing of the outer casing or the clock itself. The general principles surrounding time recorder construction are well known, and I do not believe it to be necessary to describe other than the newly developed parts invented by me.

I have indicated the framework of the machine as 1, and the time shaft coming 35 from the block (not shown) as 2. This time shaft (Figure 7) is geared to the time wheels, positioned as at 3, in front of which passes the printing ribbon 4. The time shaft is also geared to the large pinion 5, which revolves continuously the control shaft 6 for the various abutments.

Extending across the frame in front of the time wheels is a shaft 7 serving as a rock shaft for the platen hammer 8 upon 45 which shaft the hammer is secured, said shaft being tripped or rocked by the operating handle, as will be noted.

The platen hammer presses against the face of a card held in the sliding tray 10. 50 This tray comprises slotted side bars, an inserting slot and hopper 11 and a sliding plate 12, serving as an abutment for cards inserted in the slotted side bars through the hopper.

55 A cross bar 13 in the frame serves as the main support of the card tray, and the card tray support also has hooks 14^a for sliding over the rock shaft of the platen hammer.

60 A bracket 14 extends out from one end of the machine for support of the platen handle. This handle 15 is pivotally mounted on a stud 16 in the bracket and extends beyond the stud, where it supports a stub shaft or pin 18.

The rock shaft 7 which is in alignment with but terminates short of the stud 16 and is equipped with a nose 19 which serves as the rocker arm. Pivoted on the stub shaft 18 is a hook-shaped piece 20, which extends forward so as to bring a shoulder 21 thereon into juxtaposition with the rocker nose on the rock shaft. The shoulder end of this piece is held by a spring 21^a to the operating handle, and a nose 22 on 75 the other end of the said piece strikes an adjustable stop 23, held in the bracket.

This construction, which is not urged herein as novel, operates as follows: When the handle is depressed the stub shaft 18 is rocked upwardly by it, thereby causing the hook-shaped piece to pull down the rocker nose of the platen hammer rock shaft. When the abutment screw 23 contacts with the nose 22 on the hook-shaped piece, it can move no further in the same arc, as its initial movement, so that it swings around the stub shaft, thereby releasing the rocker nose and permitting the rock shaft to snap back under the tension of a coiled spring not shown, thereby throwing the platen hammer against the card in the card tray. The spring 21^a brings the hook-shaped piece back to its normal position, and the spring 9 returns the platen handle. 85

Pivoted on the stub shaft 18 is a link 25 connected to a rocker 26, and thence to a return link 27.

Erected on the base of the machine is a standard 28, which supports pivotally at 90 29 a yoke 30. This yoke has one of its arms extending outward toward the side of the machine and thence bent upwardly as at 31 and connected pivotally to the link 27. 105

When the platen hammer is depressed in printing upon a card, the link 27 is depressed and when the handle is released, the link is raised again, thereby rocking the yoke first up and then down.

Extending across the machine from the standard 28 is a shaft 32, which finds its other support in a like standard 28^a on the far side of the machine. This shaft carries a slide block, which in this instance is made up of a hollow member 33 carrying rollers 34^a which make an anti-friction bearing on the shaft. 115

Pivoted to the card tray which slides across the machine, as has been noted, is an arm 34 to which is pivotally connected a lever 35 extending downwardly. At its lower end the lever is rigidly secured to a yoke 36 which embraces the slide block 33 and is pivoted thereto at 37. The yoke also carries pivotally at its upper and lower ends on both sides of the block, a pair of fingers 38, 38, which are coupled together by a link 39, while the link 39 is also pivoted at its middle point to the sliding block. Thus when the slide block is thrust along the shaft 125 130

when one of the fingers 38 contacts with an abutment, the slide block will move until the other finger contacts with its abutment, and then the lever 35 and the card tray will be carried to a definite position.

To slide the block, the first mentioned yoke 30 is equipped at its inner end with links 40, which are pivoted to the block, thereby forming a double toggle arrangement.

10 such that when the yoke 30 is rocked, the slide block will be moved across the supporting shaft thereon. The parts are so adjusted that wherever the slide block may be stopped by the fingers, the lever 35 will be 15 shifted until the toggle construction of yoke and links 40 will be in a straight line, so as not to block the final movement of the operating handle by means of which the toggles are operated as heretofore described.

First describing the abutment elements instead of their mode of operation, it will be noted that mounted upon the shaft 32 is, in the preferred form (Figures 3, 4 and 5), a 20 disk 41 in which are set a series of abutment posts 42. As shown in development in Figure 5, these posts are arranged for seven days of the week, with two posts for each day, which when arranged in the disk form 25 are alternately long and short. As shown in development in Figure 5, the posts for the upper finger of the card positioning yoke and the lever are the seven posts on the left, while the seven posts on the right are for 30 the lower finger.

As the disk is revolved in a step-by-step movement, the locating of the card tray is accomplished by the mode of operation above referred to. The only work to be done 40 by the clock is to turn this disk one step each day (in the present machine) which is done by raising a weighted pawl.

It will be obvious that the same principles 45 of construction can be employed for the movement of the card tray instead of for days of the week for movements desired during the day such as to shift the card tray for In, Out, Morning, Afternoon and Overtime.

50 In such construction, the disk with the stops would have to be shifted six times during each day, and the days of the week would have to be changed by arranging the movement of the card tray abutment once each day, so also there might be fourteen changes per week arranged for the disk carrying the stops. Various shifting about of the operating principles of the machine could, as is obvious, be accomplished by the 55 adjusting of the positions or changing of numbers of the abutment posts.

60 I have shown a form whereby the posts are held in place by nuts 42^a. I have also shown in Figure 1 and Figure 12 a disk which instead of posts is cast with periph-

eral ribs 41^a, which take the place of the pins.

Dealing next with the operation of the abutment member noted, and also the card abutment that slides in the card tray, it was 70 noted that by suitable gearing from the clock or time shaft, I drive a large gear 5 which revolves continuously the control shaft 6.

On this shaft is a cam 43 for a particular 75 description of which I refer to my former patent. This cam actuates the raising and lowering of a yoked lever 43^a by abutting a pin 43^b attached to this yoke. The yoke holds this pin against the cam by gravity 80 and it is further held in this position by a spring member 44 which tends to hold down the free end of the yoked lever. The yoke in turn presents a blade 45 to the finger 46 on the card abutment in the card tray. 85 Once each day, in the present machine, the card abutment makes a complete cycle of movement up toward the top of the tray and back again, this movement being variable and in some instances intermittent, due 90 to the conformation of the cam.

The control shaft also carries (in this instance) a single finger 47, which revolves once a day with the shaft, and pivotally mounted on the frame is a rocker 48 which 95 lies in the path of the finger, so that it will be depressed at the rear end and then slip past the finger with a sudden rise and consequent drop at the forward end.

At the forward end of the rocker is a link 100 49^a connecting it with a yoke 49 journaled on the shaft 32. This yoke carries the pawl 50 which operates the abutment disk. For this purpose the one arm of the yoke extends upwardly as at 51 and is there 105 equipped with a pin 52 for mounting the pawl 50.

This pawl, controlled by a spring 53, 110 rides over a ratchet 53^a on the sleeve 54 of the abutment disk 41. The rocker 48 has a weight 55 at its forward end, so that the control shaft, as it revolves, once each twenty-four hours, slowly elevates the weighted end of the rocker by means of the finger 47 and then permits said weighted end to drop sharply. This pulls the small yoke 49 around the shaft 32 and enables the pawl to advance the ratchet of the abutment disk, 115 one notch.

The disk will remain in the altered position until the next pawl operation. The pawl is stopped against a pin 56 protruding from the side standard 28^a and cannot overthrow the disk, since the movement is not rapid and the pawl jams slightly behind 120 the pin 56.

To give an accurate locked position of the card tray at the time when the platen hammer hits the card, I provide the following arrangement. On the card tray is 130

mounted a rack 74, which is set on the forwardly extending arms on the tray indicated at 75.

The shaft 13 on which the tray slides is 5 a rock shaft, and set into the shaft is a pin 76, which, in normal position, lies slantingly above the rack (Figure 7). When the shaft is rocked the pin comes down against the rack and into one of the slots 10 therein, whichever one is set beneath it by the positioning mechanism above described.

The teeth in the rack have V-shaped points 77 terminating in rounded portions 78, into which the pin closely fits. Thus 15 when any notch is fairly under the pin, it will force the rack along by sliding down the slanting face of the point, and then will find its final seat in the accurately placed notch portion 78.

20 To rock the shaft in such a way that it does not bring the pin down until the tray has been positioned, I provide a pin 79 (Figure 2), which is set into the shaft 13 at its left hand end, which pin extends rearwardly where it is pulled down by a spring 80. The rocker 26, at its hub, is notched out as at 26^a, so that it does not strike the pin until it has had some movement. When 25 the rocker is moved, however, by means of the operating handle, it will first move freely about the shaft 13 until it strikes the pin 79. It will then rock the shaft clockwise (on its upward shift), and thus force 30 down the central or locating pin until it centers the rack on the tray.

There will be as many teeth in the rack as there are shifts to the tray, and it should be also noted that when the operating handle is released, the spring on the pin 79 returns the shaft to normal, in addition to the 40 action of the rocker notch. The shaft is stopped in a position to leave some free play to the rocker before it strikes the pin 79, by the pin striking against some protruding tray part or otherwise, as desired.

45 It may be observed that the construction described provides for the locating of the card tray in seven different positions under control of the time clock, but that the clock is called upon merely for duty in revolving a disk or the like. This duty is accomplished by slowly raising a weighted arm, that carries the disk operating pawl.

50 The workman places his card in the tray, allowing it to come down against the card abutment, and then presses the operating handle. This movement actuates the toggle construction made up of yoke 30 and links 40 to shift the sliding block to the right. 55 This movement carries the fingers 38 against their respective abutments, and stops the movement of the block 33 and lever 35 and fixes the position of the card tray in the proper position for the particular 60 day. The toggles are of such length that

when this point is reached, the central pivot of the toggles shall be in alinement with the pivots 29 and 37. The actuation of the hand lever 15 at the same time rocks the platen hammer rock shaft to raise the hammer, which is released as soon as the card tray reaches its final position and the hand lever is fully depressed. When the handle is released the sliding block returns with it, but the card tray lever merely swings on 70 its upper pivotal connection and does not move the tray, which has sufficient frictional stability to remain in place until a new alignment of the lever moves it to a 75 new position.

Dependent upon whether it is desired to effect the lateral shift of the tray for Morning, Afternoon and Overtime, In and Out registrations (six in all) and to have the card abutment move by steps through 80 the seven days of the week or to have the mode of operation outlined, my tray moving devices will be set up and driven in exactly the same way and a full automatic machine will be provided. Thus, instead of but one finger on the control shaft, six 85 fingers could be provided, and instead of seven sets of posts on the abutment carrying disk, there could be six, with the result of shifting the card tray sidewise for 90 Morning In, Morning Out, Afternoon In, Afternoon Out, and Overtime In and Overtime Out.

I prefer, however, to have all registrations for any one day in a vertical column, 100 since in calculating time for a workman, it is easier to work down a column of figures than to calculate across laterally.

As a modification of my device for shifting the card tray, I have shown, as in Figures 8 and 9, a structure driven from the time clock by an intermittently raised and dropped pawl, the operating parts being, 105 however, omitted.

Thus the gear 60 is driven intermittently by the clock through a distance in each step to completely change the abutment devices from one step to another. The gear 60 is on a shaft 61, which extends to the front of the machine and has thereon another gear 62. This gear meshes with the pinions 63, 63, of two abutment disks 64, 64, which are supported in a vertical plane laterally 110 of the machine.

115 The disks have steps 65 formed on their peripheries, which take the place of the pins on the abutment disks, hitherto described.

120 Two standards 66 and 67 are erected on the base of the machine. One of them carries a bell crank lever 68, which is operated from the platen operating handle. The card tray locating lever 69 has its pivot at 70 on the arm 71 swung on the standard 125 67. The arm 71 projects laterally and is 130

linked to the bell crank by a link 72. The locating lever has a pair of anti-friction rollers 73 for contact with the abutment disks.

5 When the operating handle is depressed, in this form of device, the bell crank and link are moved, which positively rocks the locating lever and brings the rollers thereon up against the peripheries of the two 10 disks. This brings about a desired alignment of the lever and a shifting of the tray, and by revolving the disks one step each day, the card tray is automatically located, as in the first instance, and without 15 calling upon the clock to do more than revolve an abutment. In this instance also the location of the tray at the time a printed impression is made on a card will be very accurate since the lever will be positively aligned prior to the release of the 20 platen operating rock shaft, and the locating device will set and hold it in a precise position for a registration.

I do not wish to be limited in my claims 25 that follow to specific mechanisms, aside from their usual mechanical equivalents in the art, because I have failed above to point out in each instance the possibility of the use of alternative but equivalent 30 structure.

Having thus described my invention, what I claim as new and desire to secure by Letters Patent, is:—

1. In a time recorder, the combination 35 with a time clock, of a movable card tray, an abutment movable in the tray to form a card stop, a locating member for the card tray, an operating handle for the recorder, operative connection from the handle to the locating member, and clock operated abutment means comprising a plurality of pairs of stops to contact with the locating member and effect a desired alignment thereof, upon operations of the said 40 handle.

2. In a time recorder, the combination 45 with a laterally movable card tray, and an operating handle for effecting time registrations, means for locating the card tray, comprising a shifting member for the tray, means for moving the same by the operating handle, and a clock controlled abutment means adapted to effect a desired position of the shifting member upon being 50 moved by the operating handle, said abutment means comprising a plurality of pairs of abutments against which the shifting member is pressed.

3. In a time recorder, clock operated 55 means for shifting a card tray abutment, a clock operated abutment means comprising a plurality of pairs of stops, an operating handle, a member connected to the card tray and to the operating handle, said member adapted to contact with both stops of

the abutment means so as to be given a desired alignment, upon depressions of the operating handle, and to swing freely without moving the card tray upon retractions of said handle.

4. In a time recorder, the combination 70 with a time clock, of a movable card tray, an abutment movable in the tray to form a card stop, a locating member for the card tray, an operating handle for the recorder, operative connection from the handle to the locating member, and clock operated abutment means comprising a plurality of pairs of stops to contact with the locating member and effect a desired alignment 75 thereof, upon operations of the said handle, said locating member being so connected to the tray and the operating handle as to swing free without moving the tray upon retractions of the handle after operations thereof.

5. In a time recorder, a card tray shifting means comprising a lever connected to the card tray, means for moving the lever by the power applied to effect registrations 90 on the recorder, and a clock controlled abutment device adapted to present a plurality of pairs of abutments to the lever to control its position at the end of the said application of power.

6. In a time clock recorder, a card tray shifting means comprising a lever connected to the card tray, means for moving the lever by the power applied to effect registrations 100 on the recorder, a revolving device operated by the clock, said device lying in the path of movement of the lever, and abutments in pairs on the revolving device to enforce a given position of the lever upon 105 its movement during the operation of the recorder.

7. In a time clock recorder, a card tray shifting means comprising a lever connected to the card tray, means for moving the lever by the power applied to effect registrations 110 on the recorder, a disk driven by the clock, and a series of pairs of abutments spaced about said disk and extending into the path of the lever, said abutments being arranged so that two contact with the lever upon its movement during operations of the recorder.

8. In a time clock, the combination with 115 a card tray and an operating handle, a sliding member operated by the handle, a lever pivotally connected to the sliding member and card tray, a clock operated abutment member, and a plurality of pivoted contact pieces on the lever adapted to strike against the abutment member upon movements of 120 the operating handle.

9. In a time clock, the combination with 125 a card tray and an operating handle, a sliding member operated by the handle, a lever pivotally connected to the sliding member

and card tray, a clock operated abutment member, and a plurality of pivoted contact pieces on the lever adapted to strike against the abutment member upon movements of the operating handle, said abutment member comprising a disk set at right angles to the path of the sliding member, and a series of abutments arranged in pairs about the face of the disk in line to engage the said contact pieces on the lever.

10. In a time clock recorder, a card tray shifting means comprising a lever connected to the card tray, means for moving the lever by the power applied to effect registrations on the recorder, a disk driven by the clock, and a series of abutments spaced about said disk in pairs and extending into the path of the lever, and a tray locating means comprising a rack, and a pin adapted to be brought into engagement with the rack by the said power after the tray has been shifted by the parts above set forth.

11. In a time recorder, the combination with a card tray and operating handle for bringing type and a platen together on opposite sides of a card in the tray, a clock controlled shifting member for the card tray, and a locating device for the card tray, both said shifting member and locating device operated by the operating handle, and said locating member comprising a toothed element on the tray, and a rocking pin adapted to come down into a tooth of said element, as and for the purpose described. 25

12. In combination, in a time recorder, a card tray, means for slidably supporting the same, comprising a rock shaft, a rack member on the tray and a pin in the rock shaft, whereby the rocking of the shaft 40 brings the pin into a tooth of the rack and locates the tray in positive position. 35

HUGH M. LAWTON.
